(57) **CLAIM**

The ornamental design for a tray for indoor plant cultivator, as shown and described.

DESCRIPTION

FIG. 1 is a front perspective view of a tray for indoor plant cultivator showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof; and,

FIG. 8 is an exploded view showing the tray for indoor plant cultivator within a broken line environment of use.

The portions of the tray for indoor plant cultivator shown in broken line form no part of the claimed design. The broken line showing of a pod, shelf, and indoor plant cultivator shown in FIG. 8 is for the purpose of illustrating environmental structure and forms no part of the claimed design.
